BOTTLE

Yves Lanvin, Paris, France, assignor to Lanvin-Parfums, Inc., New York, N. Y., a corporation of Delaware

Application October 21, 1950, Serial No. 12,645

Term of patent 14 years

(Cl. D58—9)

To all whom it may concern:

Be it known that I, Yves Lanvin, a citizen of the Republic of France, residing at Faubourg St. Honore, Paris, France, have invented a new, original, and ornamental design for a Bottle, of which the following is a specification, reference being had to the accompanying drawing, forming part thereof.

In the drawing

Fig. 1 is a front perspective view of a bottle showing my new design, the rear thereof being identical with that shown;

Fig. 2 is a top plan view thereof.

I claim:

The ornamental design for a bottle, substantially as shown and described.

YVES LANVIN.
